UNITED STATES PATENT OFFICE.

CHARLES LEA, OF BOSTON, MASSACHUSETTS, ASSIGNOR, BY MESNE ASSIGNMENTS, TO SHAWMUT ENGINEERING COMPANY, OF BOSTON, MASSACHUSETTS, A CORPORATION OF MASSACHUSETTS.

PATTERN MECHANISM.

1,417,078.

Specification of Letters Patent. Patented May 23, 1922.

Application filed April 22, 1912. Serial No. 692,468.

To all whom it may concern:

Be it known that I, CHARLES LEA, a citizen of the United States, and a resident of Boston, county of Suffolk, State of Massachusetts, (whose post-office address is corner of Freeport and Beach Streets, Dorchester, Mass.) have invented an Improvement in Pattern Mechanism, of which the following description, in connection with the accompanying drawings, is a specification, like characters on the drawings representing like parts.

This invention relates to pattern mechanism intended more particularly, though not exclusively, for textile machines such as warp drawing machines or the like.

The invention will be best understood by reference to the following description when taken in connection with the accompanying illustration showing one specific embodiment thereof, while its scope will be more particularly pointed out in the appended claims.

In the drawings:

Fig. 1 is a plan view showing the application of one form of the invention to a warp drawing machine;

Fig. 2 is a section in elevation taken on the line 2—2 in Fig. 1;

Fig. 2^a is an elevation showing a modified form of pattern sheet;

Fig. 3 is a plan in detail showing the slide for withdrawing the feeler members;

Fig. 4 is an elevation partly in section showing the slide of Fig. 3;

Fig. 5 is a rear elevation showing the clutch actuator and its driving mechanism;

Fig. 6 is a side elevation of the same;

Fig. 7 is a sectional elevation taken through one of the clutches and its pattern controlled actuating mechanism;

Fig. 8 is an elevation partly in section showing the backing roll for the perforated pattern sheet;

Fig. 9 is an end elevation of the backing roll sleeve;

Fig. 10 shows in side elevation a pattern in cylindrical form;

Fig. 11 is an end elevation of the same; and

Figs. 12, 13, 14 and 15 show washer elements of which the roll is composed.

Referring to the drawings and to the embodiment of the invention therein illustrated I have shown the same applied to a

warp drawing machine of the general type 55 shown in United States Patent No. 980,086 and British Patent No. 958 of 1907. Such application of the invention is herein shown for illustrative purposes only, the pattern mechanism illustrated having adaptation to 60 machines employed for other purposes as well as to warp drawing machines of other types than the one herein shown.

In the disclosed type of drawing in machine, the principal parts of the operating 65 mechanism only are shown (Figs. 1 and 2). In this type of machine there is provided a bed 1 upon which are appropriately supported (but not shown) the warp threads, harnesses and reed. These are sustained 70 parallel with the length of the machine and a carriage 2 provided with a drawing-in needle 3 and suitable actuating mechanism therefor is caused to traverse the warp threads and to draw successive threads 75 through selected harness eyes and between selected reed splits.

Upon the carriage 2 there is also supported a plurality of operating rods or shafts (eight in number in the machine shown in 80 Figs. 1 and 2). These rods extend lengthwise the machine and act to select and feed, according to predetermined arrangement, the warp threads, reed dents and harness eyes with reference to the path of the drawing 85 needle. The thread separating rod 4 (the outer one of the series) carries at its end adjacent the needle path suitable thread separating devices which under each full rotation of the rod present the next warp thread 90 to the action of the drawing-in needle. Another of the rods 5 at the opposite end of the series (Fig. 1) is connected to a suitable reed opener device which also, under a full rotation of the said shaft, spreads and 95 opens the reed splits. The remaining and intervening shafts 6 pass to their respective separating and feeding devices for the several harnesses which latter, in the machine illustrated, are supposed to be six in 100 number arranged in sets of two each. For each semi-revolution of a harness separator shaft, an eye of its respective harness is presented within the path of the drawing-in needle. Another semi-revolution places the 105 harness eye out of the path of the drawing-in needle.

The thread and harness separating shafts

are removably but fixedly held in sleeve sockets 7 (Fig. 1) which latter are secured each to short operating shafts 8 journaled in the upright carriage member 9. The 5 shafts 8 extend through (Figs. 1 and 7) to receive journaled support each in its respective sleeve or bushing 10. The sleeves 10 are held fixed in a second upright carriage member 11 parallel to the carriage member 9. The end of the shaft 8 is drilled to receive the sliding plunger rod 12 having fixed at its inner end the upright clutch pin 13 the latter with the plunger being movable lengthwise of the shaft 8 in a slot 15 therein so that in its retracted position it may be seated within a notch 14 in the stationary sleeve 10 or in its projected position (shown in Fig. 7) it may be seated within a notch 15 formed in the hub of the gear or 20 other driving member 16 which latter is loosely mounted upon the operating shaft 8.

From this it follows that with the plunger and its clutch pin retracted, the operating shaft and its rod are held positively fixed. 25 With the plunger rod projected and its clutch pin seated in the notch 15, the operating shaft is clutched to the gear 16 and partakes of the same movement with the gear. This construction, except for the 30 proportion or form of the driving member 16, is substantially the same with reference to each of the shafts 4, 5 and 6, referred to. By means of driving connections from the main driving shaft 17, the details of which 35 connections form no essential part of the present invention, the several driving members 16 have imparted to them movements appropriate for turning their respective operating shafts.

40 To this end, the warp separating shaft 4 is given a constant rotation at the rate of one complete revolution for each reciprocation of the drawing needle, the driving members for the harness shafts 6 being 45 turned intermittently a semi-revolution for each reciprocation of the needle and the driving member for the reed shaft being turned a full revolution for each needle reciprocation. The clutch devices are thereby 50 selectively operated in predetermined pattern arrangement and any desired sequence of operations with the various operating shafts may be had. This provides for the selection and presentation of a heddle eye 55 from one harness followed by the presentation of an eye from any other desired one of the six harnesses and the operation of the reed dent opener and warp separator either with reference to successive thread drawings or semi-occasionally only, as may 60 be desired.

In the described embodiment of my invention, I have provided means for actuating the plunger shaft 12 for the several 65 clutches as follows: For the series of

plunger shafts there is provided a common reciprocating actuating member herein consisting of the plate or casting 18 provided with a series of ears 19, adjacent pairs of which are adapted to engage each a collar 20 on the plunger shaft 12 (see Figs. 5 to 7 inclusive). The actuating plate has a journaled support at 21 in the carriage frame to permit of a rocking movement about its axis, an oscillatory movement being imparted thereto by means of the face cam 22 which engages a cam roll 23 carried upon an arm 24 depending from the plate. This serves to give a quick movement forward and then backward to the actuating plate 25 for each reciprocation of the needle. The cam 22 is mounted upon the same shaft with a gear 25 (see Figs. 1 and 2) driven through intermediate gears 26 and 27, from the main driving shaft of the machine. As the plate 20 is rocked forward it advances each collar 20 with its plunger shaft and clutches the corresponding driving member to its operating shaft causing the operating shaft to partake of the movement of the driving member which immediately follows unless the plunger is meanwhile retracted. The plunger shaft is retracted by means of the spring 28 interposed between the end of the shaft 8 and collar 20. With each forward 95 movement of the actuator the several driving members are clutched to their respective shaft, the same, however, being immediately released unless held in active position by the feeler devices herein described. 100

To prevent retraction of the plunger rod for any given clutch and thereby select for operation its corresponding operating shaft during the next cycle of needle movement, feeler members are employed which, under 105 the control of a suitable pattern device, present, at the appropriate time and behind the appropriate plunger rods, obstructions or abutments preventing the retraction of the rods. 110

This may be accomplished in various ways but herein a fixed rectangular frame is provided at the end of the carriage consisting of two frame members 32 and 33, extending transversely of the machine and the frame 115 members 34 and 35 (Figs. 1 and 2) extending longitudinally of the frame. The frame member 32 (Figs. 1 and 7) acts as a rear guide for the ends of the sliding plunger rods 12 while the members 34 and 35 slidably support and guide a series of feeler bars 36, one for each plunger rod, each feeler bar carrying an abutment consisting of an upright pin or finger 37. Each rod with its abutment finger executes a limited movement transversely the axis of its plunger rod so that, as required, the abutment finger may be interposed back of the advanced plunger rod and prevent its retraction. The feeler bars which are herein shown of rectan- 120 125 130

gular cross section, are each constantly pressed away from the supporting guide member 35 and toward the member 34 by means of a compression spring 38, one end 5 of which is hooked into a hole in the rod and the other ends abuts against a cap plate 39 secured to and overlying the frame member 35 (see Fig. 4).

The opposite active ends of the feeler bars 10 are engaged by suitable pattern devices which normally press or crowd the feeler bars back against the springs 38 maintaining them in the position shown to be occupied in Fig. 1 by the first, second, third and last 15 (from the top in Fig. 1) of the feeler bars which correspond to the six harness separator shafts 6.

The pattern device may be of any suitable form but herein the same consists of a perforated sheet 40 against which the ends of the rods rest, perforations being provided in the sheet of suitable form and location to permit each rod at predetermined intervals to move from the inactive position referred to, to an active position with its abutting finger in line with the corresponding plunger rod. This position is shown occupied by the feeler bars corresponding to the fourth and fifth harness shafts 6 counting from the top of the sheet in Fig. 1.

Any suitable relation between the pattern device and the feeler bars may be maintained, but herein the feeler bars being arranged in a parallel horizontal series, the pattern sheet is rotated about guide rollers having horizontal axes, the perforations 41 being arranged in longitudinal rows or series and transverse sets one row for each feeler bar and one set for each cycle of needle movement. The pattern sheet may be of any suitable material, but is preferably of thin sheet metal or stout paper.

To support and drive the pattern sheet 40, the latter is provided with two rows of perforations 42, one near each edge, these being adapted to receive sprocket wheel teeth 43, one set of teeth being formed upon one end of the supporting sleeve 44 (see Fig. 8), and the other upon a collar 45, the latter held 50 upon the threaded end of the sleeve 44 by the nut 46.

Between the collar 45 and the opposite toothed end of the sleeve 44 there is interposed as second sleeve 47 which constitutes a backing member for the pattern sheet 40, such backing member being provided with teeth 48 and intervening grooves (see Fig. 9), the sides of the teeth being slightly inclined away from the direction of rotation.

60 The sleeve 44 is journaled for free rotation about the fixed shaft 49 having an intermittent step-by-step movement thereon as hereinafter described, so that at each movement thereof, a new transverse set of perforations 65 on the pattern sheet and a new groove on

the backing member 47 (a groove underlying each transverse set of perforations) is brought into registration with the row of feeler bars. The sleeve 44 is retained on the fixed shaft 49 by means of the nut 50 threaded on the end of said shaft. 70

It will be evident, therefore, that as the pattern sheet is advanced one step, those feeler bars which come into registration with perforations in the pattern are immediately forced through the perforations by their springs, their ends being beveled (see Fig. 2) to enter the corresponding underlying groove of the backing member 47, bringing their abutment fingers into an active, 80 clutch-maintaining position. Those feeler bars which register with an unperforated portion of the pattern sheet, however, are held back by the latter in an inactive or clutch-releasing position. When the pattern actuating sleeve 44 undergoes its next movement, the beveled shaped teeth 48 positively force or wedge the feeler bars back by pressure against the beveled ends thereof, each of the latter being thereafter held back 90 by the pattern sheet until a perforation therein is brought to register with the end of the bar. The backing member 47 may or may not act as a limiting stop for any selected feeler bar which penetrates the pattern 95 sheet. Preferably, however, it acts as described as a positive actuator for moving back the feeler bar, relieving the pattern sheet of any undue mechanical strain thereof. The pattern sheet can therefore be made 100 relatively light and thin and suitably perforated paper sheets may be used for this purpose.

To move the pattern sheet step-by-step in synchronism with the needle reciprocations, there is provided a cam 55 (see Figs. 5 and 6) attached to the hub of the face cam 22. This cam is provided with projections which engage the cam roll 56 carried by the depending arm 57 on the sleeve 58, the latter (Figs. 110 5 and 8) mounted to oscillate on the fixed shaft 49. The sleeve 58 at one side is provided with a drum shaped member 59 (Fig. 8) which encases a ratchet wheel 60, the latter pinned to the adjacent pattern actuating sleeve 44. The drum member 59 carries a spring pressed pawl 61 engaging the teeth of the ratchet and so arranged that when the arm 56 is lifted by the cam 55 the pawl engages the teeth of the ratchet and moves 115 the latter with the actuating sleeve 44 through one step which is equivalent to the presentation of a fresh transverse set of pattern perforations, to the feeler bars.

The cams 22 and 55 are so proportioned 120 that at each retraction of the drawing-in needle, the clutch actuator 18 is immediately thrown forward and the pattern sheet simultaneously advanced one step, the selected abutment fingers 37 being interposed be- 130

hind their respective selected rods before the retraction of the clutch actuator 18, which immediately thereafter takes place.

The cam roll 53 is held against the cam 5 and the pawl 61 is reversed by a tension spring 63 connected to a lug 64 on the drum 59.

The pattern sheet may be in the form of an endless belt, the same pattern being 10 drawn and re-drawn in continued succession. When a pattern sheet of this description is employed (see Fig. 2), the same being herein shown as journaled upon the shaft 66, the latter carried by the upright 15 arm 67 is adapted to be clamped in different positions of angular adjustment on the block 68 to adapt the position of the roller to pattern sheets of different lengths.

Where a longer pattern sheet is required 20 than it is convenient to mount upon the single guide roller 65, a plurality of guide rollers may be employed mounted upon a suitable frame such as is shown in Fig. 2a. Therein an arm or upright 69 is supported 25 in the block 68 and carries upper and lower cross supports 70 and 71 on which are journaled a succession of guide rollers over which the elongated pattern sheet 72 passes in its travel. By increasing the number of 30 these guide rolls a pattern sheet of any required length may be employed.

In the case of simple patterns or under 35 other conditions it may be desirable to employ a pattern member of cylindrical or roll form in place of the member in sheet form. In Figs. 9 to 15, inclusive, I have shown the details of such cylindrical pattern member, the same being so constructed that it may be 40 adjusted to produce any required pattern. In the form illustrated twelve successive different combinations may be effected in the movements of the operating shafts before a repetition is necessary, but the number of 45 such operations, or in other words, the length of the pattern, may be increased by increasing the diameter of the cylinder.

As indicated in Fig. 10, the construction 50 of the cylindrical pattern member is similar to that of the pattern actuating member shown in Fig. 8, except that for the backing member 47 there is substituted a plurality of pattern elements, each consisting of a washer 73, there being provided one washer or pattern element for each feeler bar, these 55 being herein in connection with intervening blank or separating washers 74. The blank washer is shown in Fig. 12 and different forms of the pattern washers are shown in Figs. 13, 14 and 15. It will be seen that the 60 pattern washers are similar to the blank washers except for the notches cut in the periphery at various points, the notches performing the functions of the perforations in the pattern sheet 40. By arranging different forms of these washers in different angu-

lar positions on the sleeve the notches or recesses may be arranged to provide any desired pattern control as in the case of the pattern sheet.

Any suitable means for adjustably fixing 70 the washers upon the sleeve may be employed, but preferably an arrangement is provided whereby each washer may be shifted to any one of the twelve or other possible angular positions upon the sleeve and in that 75 position may be positively driven from the sleeve itself. To provide for this I have caused each washer to be drilled with a series of holes 75, herein twelve in number corresponding to the twelve positions of the pattern member as it is turned in its step-by-step movement. With each pattern washer adjusted to its desired angular position on the sleeve one or more wires or small rods 80 are then inserted through the holes 75 in the 85 series of washers, which holes are thus brought into alignment, the rods or wires being seated in a corresponding hole in the enlarged end of the fixed sleeve 44 and also in the collar 45 at the outer end of the sleeve. 90 This provides for the positive driving of each individual pattern member directly from the actuating sleeve itself, while at the same time it permits the adjustment of the pattern washers at any desired time to different angular positions. It also permits 95 them to be withdrawn and washers of different form substituted.

It is sometimes required to shift or change 100 the pattern, either temporarily or at some given time in the operation of the machine or under other conditions which make it impracticable or inconvenient to replace the pattern sheet by another. This may be desirable, for example, in the case of a 105 drawing-in machine for drawing the selvage at the beginning and end of the drawing-in operation. To accomplish this I have provided means for shifting the entire pattern device laterally so that a different set of 110 pattern perforations or depressions may be quickly brought at any time into alignment with the feeler bars temporarily withdrawing from registration with the feeler bars the prior set of pattern perforations. For 115 this purpose the longitudinal rows of pattern perforations are so spaced in the pattern sheet 40 as to permit the formation of intermediate rows of pattern perforations.

In the form shown in Fig. 1, for example, 120 the first row of such auxiliary pattern perforations would occur between the inner row of sprocket teeth perforations and the first or continuous row of main perforations and each successive row of auxiliary pattern perforations would be positioned between each 125 two successive rows of main pattern perforations. In the case of the cylindrical pattern member shown in Fig. 10, such auxiliary pattern member could be provided by sub- 130

stituting pattern washers for the blank washers 74 in the positions where such blank washers are shown applied to the pattern member in Fig. 10.

5 To shift the pattern member and bring into registration with the feeler bars the auxiliary pattern elements, I have arranged the actuating sleeve 44 with its connected cam actuated sleeve 58 so that it may be slid 10 longitudinally along the fixed shaft 49 and be made to occupy a position slightly to the left of the position shown in Fig. 1. In order to locate the pattern member upon the shaft the collar 46 is provided with two 15 grooves 77 and 78 in which there is adapted to seat a downwardly spring pressed finger 79 (see Fig. 1) pivoted on the frame member 34. When the finger 79 is seated in the outer groove 78, the pattern member is maintained laterally in the position shown in 20 Fig. 1. By lifting the finger 79 however, the pattern member may be slid outwardly and the finger dropped into the groove 77, whereupon auxiliary pattern perforations 25 which may be provided intermediate the main pattern perforations, are brought into registration with the feeler bars.

The operation of the controlled mechanism will be readily understood from the preceding description. With each retraction of the drawing-in needle the several clutches are thrown into engagement by the common actuator 18, but are immediately released unless held against release by the interposition 30 of an abutment 37 in the path of the corresponding plunger rod 12. For each clutch there is a corresponding movable abutment 37 and a corresponding feeler bar 36. Each feeler bar is normally held with its abutment at one 35 side of the rectilinearly movable plunger rod, but on the presentation of the perforation to the end of the feeler bar the latter is moved by its spring 38 and enters the perforation of the pattern member bringing the 40 corresponding abutment directly within the path of the clutch rod 12 so that the corresponding clutch remains engaged and its shaft is thereupon turned.

In the case of the harness eye separator 45 shafts, perforations are usually provided in succeeding pairs, so as to provide for a half turn of the separating shaft following the retraction of the needle to face an eye, followed by a second half turn to pass the eye 50 along after the next retraction of the needle. In the case of the warp thread separating shaft 4, there is ordinarily provided a pattern perforation for each needle movement, except when it is desired to stop the movement 55 of the shaft to drop a thread. In the case of the reed opener shaft perforations are ordinarily provided for each alternate thread movement this resulting in drawing two threads through each reed dent. This

order can be varied in any desired manner 65 so as to provide for any desired succession of thread, reed-dent, or harness eye selecting and presenting movements.

It will be seen that the mechanical work of throwing in and out the clutches is performed by actuating devices apart from the pattern selective mechanisms, the pattern controlling devices performing no work in and of themselves except to control the reciprocations of the light feeler bars. 70

While the abutments 37 might be made of sufficient length to hold the plunger rods 12 against retraction in and of themselves, preferably those movable abutments are merely interposed between suitably positioned fixed abutments 82 carried by the frame member 33, such abutments comprising bars projecting each from the said frame member in alignment with a plunger rod and relieving the abutments 37 and the 85 feeler bars from any undue strain.

In order to withdraw all the feeler bars simultaneously from the pattern member in order to start at a fresh point on the pattern or replace the old pattern with another, the 90 ends of the bars are notched at 83, as shown in Figs. 3 and 4, and the cap piece 39 is provided with a downward shoulder 84 resting in the notches on the bars. The cap piece is held to the underlying frame member 35 by 95 means of studs passing through slots 86 in the cap piece so that the latter may be slid back when desired by the knob 87 to withdraw all the feeler bars from the surface of the pattern sheet. If desired the shoulder 100 84 may be utilized to limit the forward movement of the feeler bars when their forward ends enter the perforations of the pattern sheet.

While I have herein shown and described 105 for purposes of illustration one specific form of the invention, it is to be understood that the same is submitted for illustrative purposes only and that extensive deviations may be made from the details of construction, location and relative arrangement of parts and the application made of the invention without departing from the spirit thereof.

Claims.

1. In a machine having a plurality of operating parts to be intermittently actuated, a series of clutch members for intermittently controlling said respective parts, a common actuator for all of said clutch members as a group, and pattern-controlled devices for rendering effective selected clutch members. 110

2. In a machine having a plurality of operating parts to be intermittently actuated, a series of clutch members for intermittently controlling said respective parts, longitudinally movable operating members, 115

- pattern controller means, and pattern controlled selecting members movable transversely said operating members.
3. In a machine having a plurality of parts to be intermittently actuated, a common actuator for all of said plurality of parts as a group, a plurality of feeler members for controlling said plurality of parts and a pattern device controlling said feeler members.
4. In a machine having a plurality of operating parts to be intermittently actuated, a series of clutch members for intermittently controlling said respective parts, a common actuator to advance all of said clutch members into operative position, and pattern controlled devices to hold selected clutch members in operative position while permitting the remaining clutch members to return to inoperative position upon the return of the common actuator.
5. The combination with a series of clutch devices of rectilinearly movable controlling means therefor, pattern controller means, and pattern controlled means for selectively controlling said clutch devices, movable across the line of clutch movement.
6. The combination with a plurality of clutch members of rectilinearly movable plunger rods therefor, pattern controller means, and pattern-controlled selecting means including an abutment member movable across the line of movement of said plunger rods.
7. The combination with a plurality of clutches to be intermittently engaged, of rectilinearly movable members for engaging the same, actuating means for said members and selecting devices adapted to be moved into the path of movement of said members for selectively controlling the engagement of said clutches.
8. The combination with a plurality of driving clutch members, means for alternately engaging and releasing the same, selective means movable across the path of movement of said clutch engaging means to maintain said clutch members applied, and pattern means to control the movement of said selective members.
9. In a pattern control machine, the combination with a plurality of members adapted to be intermittently actuated, a plurality of independently reciprocable actuating devices for the same, pattern controlled feeler members, pattern controller means, and abutment devices adapted to be moved into the path of said reciprocating devices by said feeler devices for selectively controlling the actuation of said members.
10. In a machine having a plurality of parts adapted to be actuated, the combination with rectilinearly movable members for actuating the same, means for reciprocating said members, fixed abutting means, pattern controller means and movable pattern controlled abutting means adapted to be selectively moved between said fixed abutting means and said reciprocating means to obstruct the movement of the latter.
11. The combination with a plurality of parts adapted to be intermittently actuated, clutch members for actuating the same, clutch actuating devices, a plurality of feeler members adapted to selectively control said clutch actuating devices, and a pattern control element having a plurality of recesses for controlling the movement of said feeler members.
12. In a machine having a plurality of operating parts to be intermittently actuated, a series of devices for intermittently controlling said respective parts, a common actuator to move all of said devices into operative position, and pattern controlled means to maintain selected devices in operative position while permitting the remaining devices to return to inoperative position upon return of the common actuator.
13. In a pattern-controlled mechanism, the combination with a perforated pattern member, of pattern-controlled members adapted to enter the perforations thereof, and means to engage the entered portions of said pattern-controlled members for forcibly expelling said members from the said perforations.
14. In a pattern-controlled mechanism, the combination with a perforated pattern sheet and a rectilinearly movable, plunger action pattern controlled member, of a recessed backing member therefor having pattern controlled member ejecting means.
15. In a pattern-controlled mechanism, the combination with a perforated pattern member of pattern-controlled elements adapted to enter the perforations thereof and a backing member adapted to limit the entrance of said pattern-controlled elements, said backing member having means for ejecting said pattern controlled elements.
16. In a pattern-controlled mechanism, the combination with a plurality of pattern-controlled members, a perforated pattern member through the perforations of which the said members are adapted to pass, and a backing member against which said pattern members are adapted to seat, said backing member being formed to forcibly expel said pattern-controlled elements.
17. In a pattern-controlled mechanism, the combination with a perforated pattern sheet and a rectilinearly movable, plunger action pattern controlled member of a recessed back roll therefor having pattern controlled member ejecting means.
18. In a pattern-controlled mechanism, the combination with a perforated pattern sheet of a backing member therefor, pattern-controlled elements adapted to enter the per-

forations on said sheet, and means on the backing member for forcibly expelling the pattern-controlled elements.

19. In a pattern-controlled mechanism, the combination with a rectilinearly movable, plunger action perforated pattern member, an actuating device for moving the same, and a recessed roll carried by said actuating device in cooperation with the pattern member having pattern controlled member ejecting means.

20. In a pattern-controlled mechanism, the combination with a plurality of feeler bars having beveled ends, of a perforated pattern member and a beveled backing member for engaging the ends of said bars, when the same are passed through the perforations of said pattern member.

21. In a warp drawing machine, the combination with a perforated pattern member having longitudinal rows of pattern perforations, pattern controlled elements, and means whereby said pattern member may be shifted laterally to present different rows of pattern controlled perforations to said controlled elements.

22. In a pattern-controlled mechanism, the combination with a plurality of feeler bars, and a pattern member, said member having means for simultaneously withdrawing all of said feeler bars from said pattern member.

23. In a pattern-controlled mechanism, the combination with the pattern sheet 40, feeler bars 36, operatively arranged to be selected thereby, abutments 37 operatively controlled by said feeler bars and clutch rods operatively related to and controlled in movement by said abutments.

24. In a pattern controlled mechanism, the combination of a perforated pattern member, a backing therefor having member-ejecting means and rectilinearly movable, plunger-action pattern controlled members adapted to enter perforations of said pattern member.

25. In a pattern controlled mechanism, the combination with a perforated pattern sheet, and a rectilinearly movable, plunger-action pattern controlled member, of a recessed backing member therefor, said recesses having ejecting surfaces.

26. In a machine having a plurality of actuating parts to be intermittently actuated, a plurality of reciprocatory actuating devices for the same, a common actuator to move all of said reciprocatory devices into operative position, and pattern controlled means to maintain selected devices in operative position while permitting the remaining devices to return to operative position upon return of the common actuator.

27. In a machine having a plurality of parts to be intermittently actuated, a common rocking actuator therefor, a plurality

of feeler members to select members operated by said actuator and a pattern device controlling said feeler members.

28. In a machine having a plurality of parts to be intermittently actuated, a common actuator for said parts having movement to effect common actuation of said parts and immediate release of any selected parts, a plurality of feeler members for controlling said plurality of parts, and a pattern device for controlling said feeler members.

29. In a machine having a plurality of parts to be intermittently actuated, a plurality of clutch members for said parts, a common actuator for effecting engagement of said clutches, and a plurality of feeler members for selecting the clutches to remain engaged through the action of said common actuator.

30. In a machine having a plurality of parts to be intermittently actuated, a plurality of clutches corresponding to said parts, a common actuator to effect the momentary engagement of all of said clutches, and pattern controlled means for maintaining engaged selected clutches only.

31. In a machine having a plurality of parts to be intermittently actuated, a corresponding plurality of clutches, an actuator therefor to effect momentary engagement of said clutches, and pattern controlled means for determining the continued engagement of selected clutches.

32. In a machine having a plurality of operating parts to be intermittently actuated, a plurality of devices for controlling said parts, a common actuator to move all of said devices into operative position, and means including a pattern control to maintain selected devices in operative position and to permit the remaining devices to return to inoperative position consequent upon the return of the common actuator.

33. In a machine having a plurality of operating parts to be intermittently actuated, a plurality of feeler members for controlling said plurality of parts, a common actuator to move all of said feeler devices into operative position, and means including a pattern control to maintain selected feeler devices in operative position while permitting the remaining feeler devices to return to inoperative position upon the return of the common actuator.

34. In a machine having a plurality of parts adapted to be intermittently actuated, mechanical actuating devices, feeler controlled devices for selectively establishing connection between said actuator devices and said parts, a common actuator to advance all of the feeler controlled devices into operative position, and pattern controlled devices to hold selected feeler controlling devices in operative position while permit-

ting the remaining feeler controlled devices to return to inoperative position by the return of the common actuator.

35. In combination, a perforated pattern sheet, a plurality of feeler bars controlled thereby each having an abutment, a plurality of clutch members controlled by the abutments of said feeler bars, and a plurality of parts to be intermittently actuated 10 and controlled by said clutch members.

36. In combination, a perforated pattern sheet, a plurality of parallel feeler bars controlled thereby, a plurality of parallel clutch members controlled by the feeler bars, and 15 a plurality of parts arranged in substantial parallelism and adapted to be intermittently actuated, and controlled by said clutch members.

37. A machine having a plurality of operating parts to be intermittently actuated, a series of clutch members for intermittently controlling said respective parts, a perforated pattern sheet for controlling said different clutch members, the surface thereof 25 being in substantial parallelism to the path of movement of the clutch members, feeler bars controlled by said pattern sheet and adapted to enter the perforations therein, an abutment carried by each feeler bar, a plunger rod for each clutch member and adapted 30 to engage an abutment, and a common actuator for said plunger rods.

38. A machine having a plurality of operating parts to be intermittently actuated, a series of clutch members for intermittently controlling said respective parts, a perforated pattern sheet for controlling said different clutch members, feeler bars controlled by said pattern sheet and adapted to enter 40 the perforations therein, an abutment carried by each feeler bar, a plunger rod for each clutch member and adapted to engage an abutment, and a common actuator for said plunger rods.

45. 39. A machine having a plurality of operating parts to be intermittently actuated, a series of clutch members for intermittently controlling said respective parts, a perforated pattern sheet for controlling said 50 different clutch members, the surface thereof being in substantial parallelism to the path of movement of the clutch members, feeler bars controlled by said pattern sheet and adapted to enter the perforations there- 55 in, an abutment carried by each feeler bar, and means operatively connected to the respective clutch members and adapted to be acted upon by the respective abutments.

40. A machine having a plurality of operating parts to be intermittently actuated, a series of clutch members for intermittently controlling said respective parts, a perforated pattern sheet for controlling said different clutch members, the surface thereof 60 being in substantial parallelism to the path

of movement of the clutch members, feeler bars controlled by said pattern sheet and adapted to enter the perforations therein, an abutment carried by each feeler bar, means operatively connected to the respective clutch members and adapted to be acted upon by the respective abutments, and a common actuator for said means operatively connected to the clutch members.

41. A machine having a plurality of operating parts to be intermittently actuated, a series of clutch members for intermittently controlling said respective parts, a perforated pattern sheet for controlling said different clutch members, the surface thereof being in substantial parallelism to the path of movement of the clutch members, feeler bars controlled by said pattern sheet and adapted to enter the perforations therein, an abutment carried by each feeler bar, 80 and a plunger rod for each clutch member and adapted to engage an abutment.

42. A machine having a plurality of operating parts to be intermittently actuated, a series of clutch members for intermittently controlling said respective parts, a perforated pattern sheet for controlling said different clutch members, the surface thereof being in substantial parallelism to the path of movement of the clutch members, feeler 95 bars controlled by said pattern sheet and adapted to enter the perforations therein, said plunger rods and feeler bars being movable in paths substantially normal to each other, an abutment carried by each feeler bar, a plunger rod for each clutch member and adapted to engage an abutment.

43. A machine having a plurality of operating parts to be intermittently actuated, a series of clutch members for intermittently controlling said respective parts, a perforated pattern sheet for controlling said different clutch members, the surface thereof being in substantial parallelism to the path of movement of the clutch members, 110 feeler bars controlled by said pattern sheet and adapted to enter the perforations therein, said plunger rods and feeler bars being movable in paths substantially normal to each other, an abutment carried by each 115 feeler bar, a plunger rod for each clutch member and adapted to engage an abutment and a common actuator for said plunger rods.

44. A machine having a plurality of operating parts to be intermittently actuated, a series of clutch members for intermittently controlling said respective parts, a perforated pattern sheet for controlling said different clutch members, the surface thereof 120 being in substantial parallelism to the path of movement of the clutch members, feeler bars controlled by said pattern sheet and adapted to enter the perforations therein, an abutment carried by each feeler bar, a 125 130

plunger for each clutch member and adapted to engage an abutment, and a common reciprocating actuating member adapted to engage and move said plunger rods.

5 45. A machine having a plurality of operating parts to be intermittently actuated, a series of clutch members for intermittently controlling said respective parts, a perforated pattern sheet for controlling said dif-

10 ferent clutch members, the surface thereof being in substantial parallelism to the path of movement of the clutch members, feeler bars controlled by said pattern sheet and adapted to enter the perforations therein,

15 an abutment carried by each feeler bar, a plunger rod for each clutch member and adapted to engage an abutment, and a common actuator for said plunger rods, said actuator having a to and fro movement in

20 substantially the path of said plunger rods.

46. A machine having a plurality of operating parts to be intermittently actuated, a series of clutch members for intermittently controlling said respective parts, a perforated pattern sheet for controlling said dif-

25 ferent clutch members, the surface thereof being in substantial parallelism to the path of movement of the clutch members, a back- ing member for said perforated pattern

30 sheet, said backing member having a series of longitudinal grooves each of substantially the width of the pattern sheet, feeler bars controlled by said pattern sheet and adapted to enter the perforations therein and the

35 grooves in the backing member.

47. A machine having a plurality of operating parts to be intermittently actuated, a series of clutch members for intermittently controlling said respective parts, a perforated pattern sheet for controlling said dif-

40 ferent clutch members, the surface thereof being in substantial parallelism to the path of movement of the clutch members, a back- ing member for said perforated pattern

45 sheet, said backing member having a series of longitudinal grooves each of substantially the width of the pattern sheet, feeler bars controlled by said pattern sheet and adapted to enter the perforations therein and the

50 grooves in the backing member, an abutment carried by each feeler bar, a plunger rod for each clutch member and adapted to engage an abutment, and a common actuator for said plunger rods.

55 48. A machine having a plurality of operating parts to be intermittently actuated,

a series of clutch members for intermittently controlling said respective parts, a perforated pattern sheet for controlling said different clutch members, the surface thereof being in substantial parallelism to the path of movement of the clutch members, a back- ing member having a series of longitudinal grooves each of substantially the width of the pattern sheet, feeler bars controlled by said pattern sheet and adapted to enter the perforations therein and the grooves in the backing member, said feeler bars having beveled ends, and the grooves of the backing member having a corresponding formation to act upon said beveled ends.

49. Textile mechanism comprising in combination, a plurality of harness control members, a series of clutch members for intermittently controlling said respective harness

75 control members, a common actuator to advance all of said clutch members into operative position, and pattern controlled devices to hold selected clutch members in operative position while permitting the re- 80 maining clutch members to return to inoperative position upon the return of the common actuator.

50. In a machine having a plurality of rotary shafts to be intermittently actuated, 85 a series of clutch members for intermittently controlling said respective shafts, a common actuator to advance all of said clutch members into operative position, and pattern controlled devices to hold selected clutch 90 members in operative position while permitting the remaining clutch members to return to inoperative position upon the return of the common actuator.

51. Textile mechanism comprising in combination, a thread selecting rod, a reed opener rod, a pair of clutches, clutch members for intermittently controlling said respective rods, a common actuator to advance both of said clutch members into operative 100 position, and pattern controlled devices to hold the selected clutch member in operative position while permitting the other clutch member to return to inoperative position upon the return of the common actuator. 105

In testimony whereof, I have signed my name to this specification, in the presence of two subscribing witnesses.

CHARLES LEA.
